Des. 206,388
Patented Dec. 6, 1966

206,388

COMBINATION MIXER AND GRINDER APPLIANCE

Waldemar Clemente, Rua Dr. Alvaro Alvim 76,
Sao Paulo, Brazil

Filed Feb. 16, 1966, Ser. No. 1,062

Term of patent 14 years

(Cl. D44—1)

FIG. 2

FIG. 1

FIG. 1 is a front view of a combination mixer and grinder appliance embodying my new design,
FIG. 2 is a top view thereof, and
FIG. 3 is a bottom view thereof.

The dominant feature resides in the part shown in full lines.

I claim:

The ornamental design for a combination mixer and grinder appliance, substantially as shown.
